P. E. MATTHEWS.

AUTOMATIC PAWL THROW FOR MAGNETOS OR THE LIKE.

APPLICATION FILED JULY 3, 1919.

1,376,024.

Patented Apr. 26, 1921.

FIG. 1

FIG. 2

FIG. 3

INVENTOR.

Philip E. Matthews
BY *James W. Moore*
ATTORNEYS.

UNITED STATES PATENT OFFICE.

PHILLIP E. MATTHEWS, OF PLAINFIELD, NEW JERSEY.

AUTOMATIC PAWL-THROW FOR MAGNETOS OR THE LIKE.

1,376,024.

Specification of Letters Patent. Patented Apr. 26, 1921.

Application filed July 3, 1919. Serial No. 308,602.

To all whom it may concern:

Be it known that I, PHILLIP E. MATTHEWS, a citizen of the United States, and residing in the city of Plainfield, county of Union, and State of New Jersey, have invented certain new and useful Improvements in Automatic Pawl-Throw for Magnetos or the like, of which the following is a full specification.

10 My invention is illustrated in the accompanying drawings and its particular novel features are pointed out in the annexed claims.

15 My invention relates to an automatic pawl-throw mechanism for the purpose of actuating an impulse starting coupling for an ignition generator of the type as is used in hydrocarbon engines for ignition purposes. The object of the impulse starting 20 coupling in such generators is to impart a quick mechanical starting impulse to the generator when starting the engine so as to produce a strong spark to aid the ignition at the start where the revolution number of 25 the hydrocarbon engine, produced by the cranking operation, is low. Impulse starting couplings of this character are old in the art, such a coupling being shown for instance in the U. S. Patent #1,295,633 to H. 30 Tiedemann dated February 25th, 1919.

The particular novel features comprising my invention relate to the means by which the pawl, which temporarily retards the generator armature, is thrown into engagement. 35 I have found it of great advantage to operate this pawl from the engine controlling lever, in particular from the means by which the ignition is advanced and retarded and I propose to make this connection such that 40 the pawl is thrown into engagement only when the ignition control lever of the engine is in retarded position. By this arrangement, I prevent the operator from accidentally throwing the pawl into engagement (such as might be possible if the pawl were controlled for instance from the dash board by a separate lever) with the coupling device if the spark lever is still in advanced position.

45 In the accompanying drawings, Figure 1 represents the end view of an ignition generator showing the coupling side thereof,

Fig. 2 represents the plan view of the generator portion shown in Fig. 1, certain 50 elements being shown partly in section,

Fig. 3 represents a modification of the lever connection and

Fig. 4 shows in plan view a detail of the mechanism shown in Fig. 1.

Referring to Figs. 1 and 2, 1 represents the casing of the generator, 21 the generator shaft on which is fixed a disk 2. The generator shaft protrudes far enough beyond this disk to carry rotatably mounted thereon a spring housing 3 which may contain 65 a spiral spring 20, one of whose ends is fastened to a pin 19 attached to disk 2 (see Fig. 2) and whose other end is suitably fastened to the housing 3 (fastening not shown in the drawings). Of course, the yielding 70 connection between the disk and the housing thus provided may also be effected in the manner shown in the aforementioned patent. A slotted rim 4 is provided at the spring 75 housing 3, with which a corresponding coupling member (not shown) may engage and from which the generator is driven. Thus, when spring housing 3 revolves, disk 2 by means of spring connection 20, is taken along and the generator is rotated. On disk 80 2 (Fig. 1) are provided two notches 15 diametrically oppositely disposed which operate with a pawl 6 pivoted on the magneto housing at 7. This pawl as shown in the present illustration, is subject in its motion to the action of a toggle joint which consists of a pin 10 pivotally attached at its lower end 9 to a suitably shaped portion of pawl 6 and guided at its upper end in recessed lug 11. This lug is shown in plan 85 view and in detail in Fig. 4. A compression spring 12 is disposed on pin 10 and rests at its lower end against the eye 9 of the pin and at its upper end against lug 11. Thus the pawl will be held by the toggle 90 joint either in a position in which it tends to engage one of the notches 15 of disk 2, or, if the center pin 8 of the toggle joint is thrown over to the right (indicated by dotted lines) pawl 6 will be held in a position in which it is disengaged from the periphery of disk 2 and thus prevented from engaging any of the notches 15. In that event, disk 2 can freely rotate in the direction of the arrow in Fig. 1. The holding 95 100 105 of pawl 6 in either engaging or disengaging position may also be effected for instance by the means shown in the aforementioned patent (compare therein the control of pawl 13).

On spring housing 3 is provided a cam 5, and pawl 6 protrudes far enough laterally beyond the periphery of disk 2 (see Fig. 2) so that when cam 5 arrives at the top, it 5 will disengage pawl 6 from the notch 15 in which it is located and thereby free disk 2. Thus, for instance, assuming that pawl 6 has engaged a notch 15, and assuming that by the turning over the engine spring 10 casing 3 is turned one-quarter of a turn in the direction of the arrow, Fig. 1, then disk 2 being locked by pawl 6 cannot follow and spring 20 is thereby put under tension. If, after a quarter of a turn, cam 5 arrives at 15 the top, it disengages pawl 6 from notch 15 by which disk 2 is freed so that it now will quickly snap clockwise a quarter of a turn, due to the action of spring 20. This coupling arrangement is mounted on the 20 generator shaft so that when this sudden release of disk 2 occurs, one of the pistons of the engine is at its firing stroke and this quick snappy turn of disk 2 causes the magneto to produce a strong hot spark which is 25 sufficient for starting.

The ignition generator on which my present invention has been illustrated in the drawings has means for advancing and retarding the ignition embodied in a form in 30 which the field magnets of the generator are oscillated through a certain angle corresponding with the desired degree of advance and retardation. The oscillation of this field yoke 18 (Fig. 2) is controlled by the 35 spark lever from the driver's seat (lever not shown in the drawings). Now, I propose to provide a lever 17 pivoted at 16 to the generator housing 1, whose arm 17^a protrudes into the path of the field magnet 18, 40 and whose arm 14 stands in the path of the center joint 8 of the toggle joint. Thus, when the spark is advanced and the field magnet 18 stands in the position shown in Fig. 2, arm 14 of lever 17 is removed from 45 the toggle joint so that the latter can be thrown out of engagement with disk 2 and into the position shown in dotted lines in Fig. 1. Now, in order to throw the toggle joint into the position shown in full lines 50 in Fig. 1, when it is desired to start the engine, it becomes necessary for the operator to retard his spark lever which throws field magnet 18 to the right so that thereby arm 14 of lever 17 is thrown to the left (Fig. 2) 55 which engages the toggle joint at its pivot 8 and throws pawl 6 into engagement with disk 2.

While I have shown in Figs. 1 and 2 my novel idea applied to a particular form of 60 generator, I do not wish to limit this invention to this form since it may be applied to any form of engine lever control in particular to any other form of spark advance and retard control for generators provided 65 with the impulse starting coupling of the

character described. For instance, Fig. 3 shows a lever 22 which may be connected directly with any engine control lever, in particular with the spark control lever near the operator's seat or which may be connected 70 to the spark advance and retarding mechanism of any construction which may be provided at such spark generators. This lever 22, as shown in Fig. 3, is connected with a lever 17, pivoted to the generator 75 housing 1 at 16, such that the portion 14 of this lever stands in the path of the mechanism which controls pawl 16, so that the operation is similar to the manner described with reference to Figs. 1 and 2. 80

The extent to which end 14 of lever 17 is thrown to the left in both modifications is such that when the spark control is retarded slowly, the toggle joint is brought close to the point at which it breaks to the left in 85 Fig. 1. Thus by the slow retardation of the spark lever, the pawl is not thrown into engagement with disk 1, in order to avoid such engagement in case during the running of the engine the spark should be retarded 90 for any reason. If, on the other hand, the spark lever is retarded quickly, the momentum imparted to the toggle joint will throw it over the center and it will snap to the left and cause the engagement of pawl 6 95 with disk 2.

A coil spring 23 is wound around 16, and fastened to lever 17 at one end and to a lug on the casing of generator 1. The object of this spring is to press arm of lever 100 17^a against field magnet 18, so that when the spark lever is retarded and the mechanism is about to engage the pawl when starting the engine, the arm is in a positive position against the field magnet, insuring certainty 105 that the field magnet will actuate the arm 17^a and engage 14 with 6.

I claim:—

1. In combination with an ignition generator having field magnets capable of oscillating through a predetermined angle for advancing and retarding the ignition and having an impulse starting coupling comprising an operating shaft, a driven member fastened to said shaft, a driving member associated therewith, a resilient member forming a driving connection between the driving and driven members, a pivoted pawl stop for said driven member and shaft, means operated by the driving member for 110 engaging the pawl stop to remove it from engagement with the driven member, and yielding means for holding the pawl "in" or "out" of engagement with the driven member after having been so positioned, 115 means operated by the oscillation of said magnets for throwing said pawl into engagement with said driven member when the magnets are oscillated to retard the ignition. 120

2. In combination with an ignition generator having field magnets capable of oscillating through a predetermined angle for advancing and retarding the ignition and
5 having an impulse starting coupling comprising an operating shaft, a driven member fastened to said shaft, a driving member associated therewith, a resilient member forming a driving connection between
10 the driving and driven members, a pivoted pawl stop for said driven member and shaft, means operated by the driving member for engaging the pawl stop to remove it from engagement with the driven member, and a
15 toggle joint for holding the pawl "in" or "out" of engagement with the driven member after having been so positioned, and a double arm lever pivoted on the generator housing and cooperating at one end with
20 said magnets and at the other end with the center of said toggle joint for throwing said pawl into engagement with said driven member when the magnets are oscillated to retard the ignition.

PHILLIP E. MATTHEWS.
